SPOON OR SIMILAR ARTICLE

Walter I. Bieger, Minneapolis, Minn., assignor to Arthur Salm Inc., Chicago, Ill., a corporation of Illinois

Filed Mar. 15, 1965, Ser. No. 84,255

Term of patent 14 years

(Cl. D44—29)

FIG. 1 is a perspective view of a serving spoon showing my new design;

FIG. 2 is a top plan view thereof;

FIG. 3 is a side elevational view thereof;

FIG. 4 is an enlarged cross-sectional view taken on the line 4—4 of FIG. 2;

FIG. 5 is an enlarged cross-sectional view taken on the line 5—5 of FIG. 2; and

FIG. 6 is an enlarged cross-sectional view taken on the line 6—6 of FIG. 2.

The design is intended for use on sets comprising forks and spoons and similar articles of flatware.

I claim:

The ornamental design for a spoon or similar article, substantially as shown and described.
